UNITED STATES PATENT OFFICE.

HENRY D. REY, OF AVARUA, ISLAND OF RAROTONGA, COOK ISLANDS.

JACK.

1,299,781.

Specification of Letters Patent.

Patented Apr. 8, 1919.

Application filed July 1, 1918. Serial No. 242,783.

To all whom it may concern:

Be it known that I, HENRY DANIEL REY, a citizen of the Republic of France, and a resident of Avarua, in the Island of Rarotonga, one of the Cook Islands, within the boundaries of New Zealand, have invented certain new and useful Improvements in Jacks, of which the following is a specification.

10 My invention is an improvement in jacks, and relates to those of the screw operated type, wherein pairs of toggle levers are provided, having at one end a base and at the other end a head for engaging the object to be lifted, the screw having threaded engagement with one pair of the levers and a rotatable engagement with the other at the connection of the members of the pairs, for moving said connections toward and from 20 each other when the screw is rotated.

In the drawings:

Figure 1 is a front view of the improved jack in use;

Fig. 2 is a side view;

25 Fig. 3 is an enlarged sectional detail at the top of the jack;

Fig. 4 is a front view of the screw;

Fig. 5 is a front view of the holder.

In the present embodiment of the invention, a plurality of pairs of toggle levers is provided, each pair consisting of similar sections 1 and 2, and the said sections have their adjacent ends forked, as indicated at 3, the arms of the forks being lapped upon 35 each other and pivotally connected in a manner to be described. Referring to Fig. 2 it will be noticed that the meeting faces of the arms of the sections 1 are rabbeted, as indicated at 4, to receive the arms of the sections 2, which are arranged upon the inner faces 40 of the arms of the sections 1.

A block 5 is arranged between the arms of the sections of each pair, and is pivotally connected to the arms of the sections by 45 means of stems 6 which pass outwardly from the ends of the blocks through registering openings in the lapping arms, and are headed outside of the arms, as shown in Fig. 2.

50 The ends of the sections 2 remote from the forks 3 are connected by a base 7. This base is in the form of a plate having a pair of laterally spaced upstanding lugs 8 at approximately its center, and the ends of the 55 sections 2 are pivoted between the lugs by a bolt or rivet 9.

The ends of the sections 1 of the pairs remote from the forks 3 are pivotally connected to a head 10, the said head having a pair of depending laterally spaced lugs 11, 60 between which the ends of the sections are received, and the said ends are pivotally connected to the lugs by a bolt or rivet 12. Referring to Fig. 2 it will be noticed that both the sections 1 and 2 are rabbeted at 65 their pivotal connection with the base and the head, the rabbets indicated at 13 being of sufficient depth so that the lateral faces of the sections 1 and 2 are flush with each other. Each section 2 has at the bolt 9 and 70 each section 1 has at the bolt 12 a lateral extension or lug 14, the said lugs or extensions extending at approximately a right angle to the body of the section.

When the pairs of toggle levers are adjacent to each other, that is, in a position to move the head 10 the greatest possible distance from the base 7, these lugs or extensions 14 engage the base or the head, as the case may be, as shown in Fig. 3. The pivotal 75 connections of the pairs are moved toward and from each other by a threaded rod 15 having at one end a crank 16 for convenience in manipulating the same. This rod rests in notches or recesses 5^a, in the upper faces of 80 the blocks 5, and the rod has a fixed stop or collar 17 at the end adjacent to the crank, which engages outside of the adjacent block. Near the other end a nut 18 is threaded on to 85 the rod, and this nut engages outside of the other block, the arrangement being such that when the rod is turned in one direction the stop 17 will bear against the outer face of one block and the nut 18 against the outer face 90 of the other block, and the turning of the rod 95 in the proper direction will draw the pivotal connections of the toggle levers together.

The nut 18 is prevented from rotation with the rod by its engagement with the arms of the forks 3.

100 It will be noticed, referring to Fig. 1, that the lugs 8 and 11 extend the full length of the base and the head, and the upper face of the head is concave, as shown at 19, to fit the housing 20 of the axle of an automobile, one 105 wheel of which is indicated at 21.

The improved jack is of light weight, inexpensive and very efficient for the purpose, permitting a powerful upward thrust at the ends of the line connecting the base and the 110 head. The improved jack is arranged as shown in Fig. 1, the base 7 resting upon the

ground and the head 10 engaging beneath the axle. The rod 15 already in engagement with the nut 18 is fitted in the notches 5^a of the block 5, and by turning the rod in the proper direction by means of the crank the pivotal connections of the toggle levers will be moved toward each other, to thrust upward on the head and lift the axle.

To release the axle the motion of the rod 16 is reversed, and as soon as the axle is released, by lifting the rod from the recesses of the blocks the jack may be folded into small compass for storage. It will be understood that the jack may be made in any desired size, the size depending upon the conditions to be served by the jack.

It will be evident that one rod may be used with a number of jacks as, for instance, in lifting a house, the jacks being actuated in the desired order by the rod, and the jacks are held in adjusted position by the mechanism shown in Fig. 5. The said mechanism comprises a plate or bar 21 having at each end a pair of depending lugs 22.

Each pair of lugs is adapted to engage opposite sides of a section 1 or 2, and it will be evident that when so engaged the bar will hold the parts in adjusted position, to permit removal of the rod. The bar may be engaged with the sections 1 and 2 above or below the joint. The element 16 may be engaged either above or below the rod, and does not interfere with the movement of the rod.

I claim:

1. A jack comprising a pair of toggle levers, each consisting of pivotally connected similar sections, a base pivotally connecting the pairs at one end, a head pivotally connecting the pairs at the other end, the members of each pair carrying a block at its pivotal connection, said block having a recess in its upper face and a threaded rod having near one end a fixed stop and near the other a nut and adapted to engage the recesses, the stop and the nut fitting outside of the block for the purpose specified, each member of each pair of toggle levers having at its outer end a lateral lug or extension, the lugs at each end of the levers extending in opposite directions and being adapted to engage the plate and head when the pivotal connections of the members are at their nearest point. 35 40 45 50

2. A jack comprising a pair of toggle levers, each consisting of pivotally connected similar sections, a base pivotally connecting the pairs at one end, a head pivotally connecting the pairs at the other end, the members of each pair carrying a block at its pivotal connection, said block having a recess in its upper face, and a threaded rod having near one end a fixed stop and near the other a nut and adapted to engage the recesses, the stop and the nut fitting outside of the block for the purpose specified. 55 60

HENRI D. REY.
